RETURN BEND

John E. Getzen, Birmingham, Ala., assignor to
Fred C. Fantz, Webster Groves, Mo.

Application December 29, 1932, Serial No. 649,299

3 Claims. (Cl. 285—20)

My invention relates to that class of devices which are used to connect adjacent tubes, in tube coils or nests, used in cracking apparatus. In these devices it is necessary to provide means for quickly and easily removing the return bends so as to gain access to the interior of the tubes for the purpose of removing the coke, which is deposited during the cracking process, and which must be removed at periodic intervals of more 10 or less frequency in order to assure safety of the apparatus. A further desirable feature is to permit the replacement and inspection of tubes when desired, without having to destroy the adjacent tube.

15 It is well known to operators in the refinery business that the tubes bow or sag and warp. By my improved construction it becomes possible to turn these warped tubes over thereby greatly increasing their life. It is also possible to 20 move them to a less hazardous portion of the still, thus increasing the life of the equipment.

25 My invention has for its principal object to provide a demountable tube securing housing in which the housing itself, as well as the return bend, may be quickly and easily removed, thus avoiding any difficulty or danger of the return bend sticking to the end of the tube due to coking.

30 My means of accomplishing the foregoing object may be more readily understood by having reference to the accompanying drawings, which are hereunto annexed and are a part of this specification, in which—

Fig. 1 is a side elevation of my improved device;
Fig. 2 is an end elevation of the same;

35 Fig. 3 is a cross section taken on the line 3—3 in Fig. 1; and

Figs. 4, 5 and 6 are detail views of the different parts of the invention.

Similar reference numerals refer to similar 40 parts throughout the entire description.

As shown in the drawings, I provide a return bend 1, which is of the conventional type, and is adapted to connect a pair of still tubes 2 and 3. These tubes are mounted in a plate 4, which has 45 annular members 5 and 6 at each end. These annular members 5 and 6 are connected by a central web 7. The ends of the tubes are upset as clearly seen in Fig. 1, where the exterior wall is broken away so as to show the tube mounting.

50 Intermediate the shoulders formed by the upset portions of the tube and the interior wall of the annular portions, I mount a sectional metal ring or bushing. Each of the annular members 5 and 6 are provided with radially extending lugs 55 8 and 9, the lower surfaces of which taper down-

wardly as clearly seen in Fig. 2. I provide two pairs of arcuate side walls 10 and 11. These side walls are provided with slots 12 and 13, which are fitted to and adapted to register with the radially extending lugs 8 and 9 formed on the annular 60 members.

Adjacent to the upper ends of the arcuate side walls 10 and 11 are formed slots 13 and 14, in which I mount toggles 16. In these toggles I place set screws 17, the inner ends of which are 65 adapted to engage abutments 18 and 19 formed on the external surface of the return bend 1.

The device is assembled in the following manner: The annular members 5 and 6 are clipped over the ends of the tube, the metal bushings 70 are inserted and the annular members 5 and 6 are moved back until the shoulders are locked with the shoulders on the bushing which engages shoulders on the inner wall of the annular members 5 and 6. The arcuate side walls are then 75 placed so that the slots 12 and 13 engage the radially extending lugs 8 and 9. The return bend 1 is placed in position, the toggles 16 are slipped into the slots 14 and 15, adjacent the upper ends of the arcuate side walls. The set screws 17 are 80 tightened and this forces the return bend tightly against the ends of the tubes, forming a leak-proof joint.

It will be apparent that by loosening the set screws and pushing down on the side walls that 85 they will instantly be disengaged from the radially extending lugs when the side walls, toggles, and return bend 1, can be lifted quickly and easily from the ends of the tubes. This permits access to the interior of the tubes for cleaning purposes, or if desired, the tubes can be withdrawn out of either of the annular members so as to either replace them in a different place or put a new tube in or to turn them over in the event 90 they have sagged.

Having described my invention what I regard as new and desire to secure by Letters Patent is:

1. In a refinery apparatus, a conventional return bend adapted to connect a pair of still tubes to provide a passageway therethrough, a pair 100 of annular members each of which is adapted to encircle one of said tubes and be locked thereto, radially projecting lugs on said members, the lower walls of said lugs tapering downwardly, means to connect said annular members, pairs of 105 arcuate side walls having slots which fit said lugs, detachable means mounted in said side walls, set screws therein to force said return bend into a leak-proof joint.

2. In a refinery apparatus, a conventional re- 110

turn bend adapted to connect a pair of still tubes to provide a passageway therethrough, shoulders on said tubes, a pair of annular members sectional metal bushings intermediate said annular members and said tubes, means to connect said annular members, pairs of arcuate side walls, one pair of each tube, means on said annular members which engage said arcuate side walls and detachable means mounted in the said side walls adjacent their upper ends, set screws mounted in said means, which engage said return bend to form a leak-proof joint.

3. In a refinery apparatus, a conventional re-
